UNITED STATES PATENT OFFICE.

MATTI WAINOLA, OF NEW YORK, N. Y.

TOOL.

1,237,126.

Specification of Letters Patent. Patented Aug. 14, 1917.

Application filed January 23, 1917. Serial No. 143,961.

To all whom it may concern:

Be it known that I, MATTI WAINOLA, residing at New York, in the county of New York and State of New York, have invented 5 new and useful Improvements in Tools, of which the following is a specification.

This invention has reference to improvements in tools.

In carrying out my invention, it is my 10 purpose to produce a tool comprising a comparatively straight member having an arched lateral extension at one of its ends, the inner edge of which being notched, to further provide the straight member, adjacent 15 its said end with a pivoted jaw and to arrange within the said member means, operative exteriorly thereof for swinging and retaining the jaw toward or away from the notched end of the straight member, where- 20 by objects of various sizes may be secured and operated upon by the jaw and the notched arched member.

With the above and other objects in view 25 the improvement resides in the construction, combination and arrangement of parts set forth in the following specification and falling within the scope of the appended claims.

In the drawing:

Figure 1 is an edge elevation of a tool 30 constructed in accordance with this invention, parts being broken away and parts being shown in section,

Fig. 2 is a central longitudinal sectional view through the same.

35 The tool is broadly indicated by the numeral 1 and includes a head 2, of steel or other suitable metal shaped in the usual manner to provide the pounding end 3 and the claw 4, while the handle 5 has one of 40 its ends received in the usual socket in the head between the pounding end and claw.

The head 2 at the outer end thereof is 45 centrally formed with a transverse notch, and the side walls, provided by the said notch are preferably beveled, it being understood that the notch extends through the socket of the head, and consequently through one end of the handle 5. The claw 4, upon the inner face thereof, is notched trans- 50 versely to provide a plurality of steps 6.

The handle 5, at the portion thereof received in the socket of the head may be, for a determined length, slotted or bifurcated, or otherwise the tool may be provided with 55 a transverse pocket 7 within which is arranged a flat segmental member 8. This

member 8 has its outer and reduced end notched, as at 9, and is pivoted, as at 10, inward of the notch. The notch 9 is arranged opposite the notch in the head 2, 60 heretofore referred to, and the side walls provided by the notch 9 may be sharpened and so it will be apparent that when the segment 8 is swung upon its pivot 10 it will move over the end walls of the notch 65 in the hammer head, and consequently a wire or the like arranged in the alining notches will be severed. The member 8 has its edge disposed opposite the stepped face of the claw 4 formed with transverse teeth 70 or serrations 11, and the wider end of the said member 8 is rounded, being struck concentrically from its pivot 10 and provided with transversely arranged teeth 12. The numeral 13 designates a shaft journaled in 75 suitable bearings in the handle and provided with gear teeth 14 and with a worm 15; the latter engaging with the teeth 12 of the member 8. The gear teeth are engaged by 80 a worm 16 formed upon one end of a shaft 85 17 that passes through a central opening in the handle. This shaft is journaled in suitable bearings that prevent the longitudinal movement thereof, and the end of the said shaft that projects through the outer end 90 of the handle is threaded, and the said shaft inward of its threads is formed with a square or rectangular portion 18. It should be stated that the outer end of the handle is rounded, whereby to receive the flange 19 95 of an operating cup-shaped member or cap 20. The member 20 is centrally formed with a square or rectangular opening to receive the square or rectangular portion 18 of the shaft, while the threaded end of the 95 said shaft is engaged by a wing nut 20.

The side or flange 19 of the operating member 20 is preferably milled to materially aid the operator in gripping the member and in turning the said shaft which 100 through the medium of the worm thereon intermeshing with the gear teeth on the short shaft 13 revolves the said shaft, causing the worm 15 which engages with the teeth of the member 8 to turn the said member upon its pivot, to bring the roughened or serrated edge of the member 8 toward or away from the stepped face of the claw. The claw, it will be noted, provides the stationary jaw of the wrench, while the member 8 provides the movable jaw for the said wrench. The arrangement of the inter- 105 110

meshing parts which actuate the movable or swinging jaw is such as to effectively hold the jaw in its adjusted position, and to prevent the accidental rotation of the shaft by the operating member 20, the wing nut 21 may be screwed tight against the cap causing the said cap to bind on the end of the handle.

The operation and advantages of the device will, it is thought, be apparent without further description, and it is to be understood that while I have illustrated and described a satisfactory embodiment of the improvement as it now appears to me, changes in size, proportion, etc., as fall within the scope of the appended claims, may be made if desired.

Having thus described the invention, what I claim is:

- 20 1. In combination with a comparatively straight member having an arched lateral extension at one of the ends thereof and the inner edge of the said extension being notched and said member opposite the said extension being slotted, of a pivoted jaw within the slot having one of its ends concentric with the pivot and the said end provided with teeth, a revoluble toothed element journaled in the said member, and co-acting with the teeth of the jaw, and an operating element for the said notched ele-

ment including a head arranged at the end of the member opposite that provided with the lateral extension.

2. In combination with a comparatively straight member having one of its ends formed with an arched lateral extension having the inner face thereof notched, and the said member, opposite the said extension being slotted, longitudinally, a jaw member pivoted in the said slot having a serrated side and a toothed edge, and the said edge being disposed concentric of the pivot of the said jaw, a shaft journaled in the member, said shaft being formed with a worm engaging with the teeth of the jaw, gear teeth upon the shaft to one side of the worm, an operating member extending centrally through the referred to straight member and being journaled therein, a worm upon the operating member co-engaging with the gear teeth of the shaft, and a disk shaped cap member secured to the operating member and arranged to contact with the end of the said straight member.

In testimony whereof I, affix my signature in presence of two witnesses.

MATTI WAINOLA.
